DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

STEAM-SUPERHEATER.

1,399,773.

Specification of Letters Patent.

Patented Dec. 13, 1921.

Original application filed August 13, 1915, Serial No. 45,399. Divided and this application filed November 27, 1920. Serial No. 426,758.

To all whom it may concern:

Be it known that I, DAVID S. JACOBUS, a citizen of the United States, residing at Jersey City, in the county of Hudson and State 5 of New Jersey, have invented certain new and useful Improvements in Steam-Superheaters, of which the following is a specification.

My invention relates to independently-fired steam superheaters and my present 10 application, which is a division of my prior application Serial No. 45,399 which was filed in the Patent Office August 13, 1915, more particularly relates to a superheater 15 having a plurality of chambers and a superheater section in each chamber, the section in the first chamber being so arranged that it is protected from the radiant heat from the combustion chamber.

20 My invention will best be understood by reference to the accompanying drawings, in which Figure 1 is a vertical longitudinal section through a separately fired superheater embodying my invention, and Fig. 2 is a horizontal section taken on the plane of the lines 2-2 of Fig. 1.

In the drawings, the numeral 1 designates a suitable setting made up of brick and structural work and adapted to inclose the 25 superheater headers and tubes. At one end of the setting is a furnace 2 beyond which is a vertical wall 3, forming with the front wall, a combustion chamber 4. The space between the wall 3 and the rear wall of the 30 setting is divided into a series of chambers by vertical walls or baffles 6 and 7 so arranged as to provide for successive down and up passes for the gases from the combustion chamber to the flue outlet 39, the 35 walls 6 and 7 being provided with openings 24 and 25, respectively, to permit the gases to flow from one chamber to the next. In each chamber is located a section of the superheater, each section being shown as 40 consisting of lower inlet and outlet headers supported in the side walls of the setting. The headers are of sufficient diameter to give the desired velocity of steam through the superheater, and are shown as flattened 45 at top and bottom. The superheater tubes 50

are bent to a U-shape and their lower ends are expanded into seats in the upper part of the headers and extend upward from the headers to the upper part of the chambers in which the sections are located, with the exception of the first section, the top of which is preferably below the wall 3, as will be more fully hereinafter explained. Opposite each tube end, the header has a hand-hole which gives access to the ends of the 60 tubes for expanding and for inspection.

I have arranged, in the construction here shown, to first admit the steam to the bank of tubes the most remote from the furnace and to cause it to flow through the superheater in a direction the reverse of the flow of the gases. The steam enters through the valved pipe 32 into the inlet header 33 and, after flowing through the tubes 34, enters the outlet header 35, thence through the 65 connection 36, outside of the setting wall of the superheater, to the inlet header 37 of the middle bank of tubes, and so on to the outlet header 38 of the bank nearest the furnace, and thence to the main steam outlet 39. 70 This arrangement for the flow of the steam is especially applicable where the bank of tubes which comes nearest the furnace is made shorter than the others. It will thus be seen that the arrangement of piping 75 which connects the headers of one section of the superheater to another section is such that the steam enters one header of a given bank of tubes at one side of the superheater and leaves the other header of the same bank 80 at the opposite side of the superheater, thus leading to a more uniform flow of steam through the superheater tubes than could be obtained should the same enter and leave the 85 headers at the same side of the setting. 90

The course of the gases is from the secondary combustion chamber at the rear of the furnace, over the wall 3, downwardly over the tubes of the first bank, and then in a general upward and downward direction 95 over the tubes of the middle and rear banks, respectively, to the outlet flue 39.

Dusting doors 40 are provided in the sides of the setting for inserting an air or steam lance for blowing the soot and dust from 100

the interior surfaces of the superheater tubes; part of the dust will be blown away with the gases, and part will settle in the dust pockets 41 beneath the superheater headers.

While the gases have a general downward and upward flow through the chambers, I prefer to use baffle shelves 27 supported partly upon the headers, and partly upon abutments projecting from the vertical division walls, to cause the gases to cross and recross the superheater tubes. The headers are preferably placed at different levels, as shown, the first header being at a higher level in a section where the gases enter at the top and leave at the bottom, and lower in a section where the gases enter at the bottom and leave at the top. By that arrangement, the gases are given a more uniform distribution over the tubes extending upwardly from the headers.

In order that all parts of the superheater surface shall be accessible for inspection and for cleaning, I provide doors 28 in the sides of the setting below the level of the headers, and doors 29 in the side and near the top of the setting above the superheater loops. I also provide doors 30 opening into the combustion chamber, which doors may be opened, if necessary, to permit cold air to enter the superheater and prevent excessive superheat.

The tubes 31 of the superheater bank, which come nearest the furnace, are made shorter than the tubes of the other banks so as to bring the top of the first bank below the top of the wall 3. By making the tubes of the first bank shorter, they are not subjected to the direct action of the radiant heat from the combustion chamber, and it makes possible to obtain a greater heat-absorbing capacity from the superheater as a whole, without danger of burning the tubes of the first bank or section. Where superheaters are used to superheat the steam to the highest attainable degree, the tubes which come nearest the fire eventually burn out and have to be replaced. It is especially desirable in such a case to make the tubes of the first bank shorter than those of the other banks, as in addition to securing a longer life for the tubes when made shorter, the cost of replacing the bank nearest the fire when the tubes eventually burn out will be less than should it be made up of the longer tubes.

What I claim and desire to secure by Letters Patent of the United States is:

1. An independently-fired superheater comprising a setting, division walls therein to provide a plurality of chambers, said walls being provided with openings to permit the gases to flow through said chambers, a superheater section in each of said chambers, a wall disposed in front of the first sec-

tion of the superheater and forming with the setting a secondary combustion chamber, the ends of the tubes of the first section of the superheater being short of the opening from the secondary combustion chamber to the first superheater chamber.

2. An independently-fired superheater comprising a setting, division walls therein to provide a plurality of chambers, said walls being provided with openings, to permit the gases to flow through said chambers, a superheater section in each of said chambers, a wall disposed in front of the first section of the superheater and forming with the setting a secondary combustion chamber, the ends of the tubes of the first section being below the top of said wall.

3. An independently-fired superheater comprising a setting, division walls therein to provide a plurality of chambers, said walls being provided with openings to permit the gases to flow through said chambers, a superheater section in each of said chambers, a wall disposed in front of the first section of the superheater and forming with the setting a secondary combustion chamber, the tubes of the first section being shorter than those of the remaining sections and the tops of the tubes of the first section being located below the top of said wall.

4. An independently-fired superheater comprising a setting, division walls therein to provide a plurality of chambers, said walls being provided with openings to permit the gases to flow through said chambers, a superheater section in each of said chambers, a wall disposed in front of the first section of the superheater and forming with the setting a secondary combustion chamber, the ends of the tubes of the first section of the superheater being located below the top of said wall, the steam entering the rear section of the superheater and flowing forwardly progressively through said sections.

5. An independently-fired superheater comprising a suitable setting, division walls therein to provide a plurality of chambers, a superheater section in each of said chambers, said walls having openings therein to permit a flow of the gases through the chambers, a furnace, a wall at the rear of the furnace to provide a secondary combustion chamber and separating said chamber from the first bank of tubes, the tubes of said first bank being shorter than the height of said last-named wall.

6. An independently-fired superheater comprising a suitable setting, division walls therein to provide a plurality of chambers, a superheater section in each of said chambers, said walls having openings therein to permit a flow of gases through the chambers successively, a combustion chamber at one end of the setting, and an opening from the combustion chamber into the top of the first

superheater chamber, the top of the tubes of the first superheater section being below the opening in the front wall, and the tubes of the remaining superheater sections extending substantially to the top of their respective chambers.

7. An independently-fired superheater

comprising a plurality of banks of tubes, and means for directing the heated gases over said banks successively, the tubes in the 10 bank over which the gases first flow being made shorter than the others.

DAVID S. JACOBUS.
